UNITED STATES PATENT OFFICE.

ROY G. SPENCER, OF SEATTLE, WASHINGTON.

TOY RAILROAD.

Application filed April 21, 1925. Serial No. 24,827.

To all whom it may concern:

Be it known that I, ROY G. SPENCER, a citizen of the United States, residing at Seattle, in the county of King and State of Washington, have invented certain new and useful Improvements in Toy Railroads, of which the following is a specification.

This invention relates to an improved toy railroad, and it has reference to a structure of this kind which embodies a base acting as a roadbed, and novel means for yieldably supporting and clamping the tracks upon the base.

One aim is to provide a road bed which is made up of detachably connected sections of shape and size to permit the complete bed to be made for accommodating a circular, ovate, or other configuration of track.

A further aim is to provide elastic means to be interposed between the road bed sections and the track cross ties, to absorb shocks and to eliminate undue noise.

Other objects, advantages, and features of the invention will become apparent from the following description and drawings.

In the accompanying drawings, forming a part of this application, and in which like numerals are employed to designate like parts throughout the same;

Figure 1 is a top plan view of a fragment of a toy railroad constructed in accordance with the present invention.

Figure 2 is a longitudinal section through the same.

Figure 3 is an enlarged transverse section taken approximately upon the plane of the line 3—3 of Figure 1.

Figure 4 is a perspective view of a clamp.

Figure 5 is a like view of a different embodiment of this clamp.

Figure 6 is a view like Figure 3, showing a different method of mounting the tracks upon the road bed.

Figure 7 is a perspective view of the type of clamp used in Figure 6.

Figure 8 is a diagrammatic plan view showing one form of completed road bed.

As before intimated, the invention is characterized in one instance by the provision of a novel imitation road bed. To explain, it is to be said that this road bed is naturally of a shape having an outline quite similar to the outline marked by the particular formation of track to be placed thereon. As is customary in tracks of this kind, the major portion will be either circular in top

plan or somewhat ovate in top plan. The road bed must therefore be made up of sections which will permit them to be formulated in one of these two outlines. In the disclosure, the roadbed is formed of a plurality of relatively thin oblong boards 1, each board having a substantially V-shaped notch formed at one end and a V-shaped projection 2 at its opposite end. The projection 2 is adapted for reception in the complementary notch in the adjacent board. The boards are to be arranged in end to end abutting relation in the same horizontal plane and to permit them to be set up upon a table or polished floor, they are provided on their undersides with rubber buttons 3. These will prevent marring of the surface upon which they rest. In Figure 8, I have shown a road bed, the marginal shape of which is substantially ovate, and in this connection it will be observed that the boards will vary in design to permit them to be fitted in place in roadbeds of various shapes. In all instances, substantially channel shaped connecting members 4 are provided. It will be necessary that these connecting channels 4 vary in design to permit them to be placed in different locations. In all instances, they will be detachably secured in place by screws or the like 5. From this it will be seen that I have evolved and produced a novel roadbed which is composed of sections of various shapes and sizes, arranged to provide any desired shape, the sections being detachably connected together in a manner to permit them to be readily dismantled to be stored away.

In addition to the roadbed, the invention comprehends novel means for mounting the track 6 thereon. In this connection, it will be seen that the track is made up of outer rails 7 for reception of the wheels of the train, and a central rail 8 adapted to conduct electricity. It is of course not essential, but preferable, to construct the device for accommodating electrically operated trains. As is usual, the rails are connected together by cross ties 9 of customary cross section. These cross ties are connected to the base or bed in two different ways. In Figures 2 and 3, one form of connection is shown, and in Figure 6, another form is shown. In Figures 2 and 3, it will be seen that wooden blocks 10, serving as sub-ties, rest upon the boards 1. A sheet of rubber 11 is arranged upon the top and bottom

of each block, so that the block serves as a shock absorber. Novel clamps (shown better in Figures 4 and 5) are employed for simultaneously mounting these blocks in place and connecting the ties 9 thereto. In Figure 4 I show a clamp embodying an arch 12 provided on one end with a depending stop flange 13, the arms of the arch being provided with angularly directed apertured attaching ears 14. The ears are detachably fastened to the base boards by appropriate fastenings. The bight portion of each arch is provided with a right angular clamping finger 15, and this is adapted to engage over the opposite end extension of the adjacent tie 9 where the sections of the tracks are joined together. Between the joints, the arch is simply provided with a single tongue 15 as shown in Figure 5. 20 Otherwise, the two clamps are identical. The clamping tongues 15 may be resilient to permit ready connection and disconnection of the cross tie.

In Figure 6, the spacing flaps are eliminated and a sheet of rubber 16 is simply interposed between the cross tie 9 and the base board 1. Under this construction, the clamp 17 varies slightly, the same embodying a horizontally apertured attaching 25 flange 18, and an upstanding intermediate portion 19, and a pair of tongues 20, to take over the end portions of the cross ties. This form is less expensive and in some instances is probably just as satisfactory. 30 In the first construction, the tracks are spaced above the base board and this is advantageous under some conditions.

From the foregoing description it will be seen that the novel toy railroad has 40 been provided, which embodies a sectional roadbed, capable of being assembled to meet the requirements of any particular conditions, the same being such that it will accommodate the ordinary marketed track sections of the various shapes and sizes. 45 The shocks to which the track is ordinarily

subjected are absorbed by the elastic subties upon which they rest, and the novel means which serves to simultaneously hold the tracks upon the sub ties and the sub ties upon the base boards is a feature upon which emphasis is to be laid. It is thought that these details will become readily apparent after the description is considered in connection with the drawings. 55 Therefore, a more lengthy description is thought unnecessary.

While the preferred embodiment of the invention has been shown and described, it is to be understood that minor changes 60 coming within the field of invention claimed may be resorted to, if desired.

I claim:

1. In a toy railroad of the class described, a sectional track and an artificial roadbed 65 therefor, said roadbed being made up of a plurality of base boards having adjacent ends arranged in abutting relation, and channel shaped connectors fitted upon the opposite longitudinal edges of the boards 70 and bridging the joints between the abutting ends, said connectors being detachably connected with said boards.

2. In a toy railroad, a base, a track upon said base, resilient means interposed between 75 said track and base, said track including cross ties, and means for detachably holding the cross ties of the track upon said resilient means, said holding means embodying resilient tongues engageable with the extended end portions of the cross ties. 80

3. In a toy railroad structure, a sectional base, sub-ties upon said base, resilient means on said sub-ties, a track including cross ties resting upon the resilient means of said 85 sub-ties, and clamps for simultaneously holding said sub-ties upon the base and said cross ties upon said sub-ties.

In testimony whereof I affix my signature.

ROY G. SPENCER.
